UNITED STATES PATENT OFFICE.

LORENZO D. VAUGHN AND THEODORE MILLER, OF GRAFTON, WEST VIRGINIA.

LAMP-IGNITER.

1,173,903.

Specification of Letters Patent. Patented Feb. 29, 1916.

Application filed April 11, 1914. Serial No. 831,176.

To all whom it may concern:

Be it known that we, LORENZO D. VAUGHN and THEODORE MILLER, citizens of the United States, residing at Grafton, in the 5 county of Taylor and State of West Virginia, have invented certain new and useful Improvements in Lamp-Igniters, of which the following is a specification.

This invention relates to new and useful 10 improvements in lamp igniters, and has for its principal object to provide an attachment which is arranged to be secured to a miner's safety lamp.

Another object of the invention is to pro- 15 vide an attachment which is arranged to house the upper end of the wick of a lamp and confine the sparks given off by the igniter, within the housing.

A further object of the invention is to 20 provide a safety lamp which may be ignited without the use of matches or any other similar igniter.

A still further object of the invention is to 25 provide a shield or housing to prevent the sparks from the igniter, from flying above the globe of the lamp and lodging against the gauze.

With these and other objects in view, the 30 invention consists in the novel combination and arrangement of parts which will be fully set forth in the following specification and accompanying drawings, in which,

Figure 1 is a sectional view of a lamp font showing the igniter as it would appear applied thereto, Fig. 2 is a longitudinal sectional view taken on line 2—2 of Fig. 1, and Fig. 3 is a transverse sectional view taken on line 3—3 of Fig. 1.

Referring now to the drawings by characters of reference, the numeral 1 designates 40 as an entirety a lamp font which is formed of a cylindrical piece of metal 2, having the bottom 3. A suitable top 4 is secured at the end of the cylindrical portion opposite 45 the bottom and is provided with the wick tube receiving aperture 5, the use of which will appear as the description proceeds. The wick tube 6 carrying the wick 7 is adapted to extend through the tube receiving aperture 5 and hold the wick in the proper position in the lamp.

A suitable aperture 8 is formed in the top 4 near the wick tube receiving aperture 5 and is arranged to aline with the aperture 9 55 and coöperate therewith in holding the

igniter tube 10 in proper position within the font.

The igniter which is designated generally by the numeral 11, comprises the supporting frame 12 having the hook member 13 60 formed at one end, which hook member is arranged to partially surround the wick tube 6 to insure the igniter being held in proper relation to the wick. This frame 12 is provided near one end with the upwardly 65 extending portion 14 having formed therein a suitable aperture 15 for the reception of the tube 16 in which the igniting material 17 is housed. A suitable spring 18 is also held within the housing 16 and arranged to exert 70 pressure against the igniting material 17 to hold the same firmly against the toothed wheel 19 which is rotatably mounted between the parallel arms 20 which are formed integral with the tube 16 hereinbefore de- 75 scribed. These arms 20 are provided with the apertures 21 near their ends, which are arranged to receive the reduced end 22 of the shaft 23 which extends through the tube 10 and is arranged to rotate when the device 80 is in use. Secured to the shaft near the reduced portion 22 is a suitable ratchet wheel 24 which is arranged to coöperate with the pawl 25 to prevent the shaft 23 from rotating in a reverse direction. The end of the 85 shaft 23 opposite the reduced portion 22 is provided with the reduced squared portion 26 which is arranged to extend into the squared aperture formed in the end of the thumb piece 27 as clearly shown in Fig. 1. 90

A suitable housing designated generally by the numeral 28 is secured to the frame 12 of the igniter, and comprises the sheet metal body portion 29 having the wick receiving aperture 30 formed therein, through 95 which the upper end of the wick 7 extends when the device is in use.

It will be evident from the foregoing that in use the thumb piece 27 is placed in position on the rectangular extension 26 and 100 forced upwardly so the end of the wick tube is below the upper wall of the housing. Upon rotating the said thumb piece 27 the sparks made by the contact of the wheel 19 with the igniting material 17 will fly horizontally and ignite the end of the wick 7, thus causing the same to ignite. It will 105 also be apparent that in the use of the housing 28, the sparks will be confined to the interior of the housing, and any danger 110

of the sparks flying above the globe of the lamp and lodging against the gauze, will be eliminated. Upon releasing the thumb piece 27 it will be evident that the frame and housing will drop back to their normal position shown in Fig. 1, thus leaving the wick and flame above the housing.

While in the foregoing there has been shown and described the preferred embodiment of this invention, it is to be understood that such changes may be made in the combination and arrangement of parts as will fall within the spirit and scope of the invention as defined in the appended claims.

Having thus described our invention, we claim:

An igniter for miners' lamps including the combination with a lamp font, a wick tube extending into the lamp font, and an

igniter tube extending through the lamp 20 font, of a clip, a hook on the end of the clip arranged to engage the wick tube and be slidably thereon to hold the clip in proper position with relation to the wick, a shaft 25 arranged to extend through the igniter tube, igniting means operatively mounted on the shaft, and a hood surrounding the shaft and the wick tube, said hood, clip, and igniter adapted to be raised above the wick tube to cause the sparks from the igniter to be directed against the wick.

In testimony whereof we affix our signatures in presence of two witnesses.

LORENZO D. VAUGHN.
THEODORE MILLER.
